UNITED STATES PATENT OFFICE

138,796

DESIGN FOR A PLASTIC SAFETY HELMET

William B. Zurfehr, St. Louis, and Vincent J. Berardino, Velda Village, Mo., assignors to General Fibre Company, St. Louis, Mo., a corporation of Missouri

Application July 17, 1944, Serial No. 114,436
Term of patent 14 years

(Cl. D3—13)

To all whom it may concern:

Be it known that we, William B. Zurfehr and Vincent J. Berardino, citizens of the United States and residents of the city of St. Louis and State of Missouri, and of Velda Village, in the county of St. Louis and State of Missouri, respectively, have invented a new, original, and ornamental Design for Plastic Safety Helmet, of which the following is a specification, reference being had to the accompanying drawing, forming part thereof.

Fig. 1 is a top plan view of a plastic safety helmet, showing our new design,

Fig. 2 is a side elevational view of said helmet,

Fig. 3 is a front elevational view of said helmet; and

Fig. 4 is a bottom plan view of said helmet.

We claim:

The ornamental design for a plastic safety helmet, as shown.

WILLIAM B. ZURFEHR.
VINCENT J. BERARDINO.
